WALTER V. TURNER, OF EDGEWOOD, PENNSYLVANIA, ASSIGNOR TO THE WESTINGHOUSE AIR BRAKE COMPANY, OF PITTSBURGH, PENNSYLVANIA, A CORPORATION OF PENNSYLVANIA.

TRAIN-PIPE VENT-VALVE DEVICE.

1,114,821.

Specification of Letters Patent. Patented Oct. 27, 1914.

Application filed May 9, 1910. Serial No. 560,235.

To all whom it may concern:

Be it known that I, WALTER V. TURNER, a citizen of the United States, residing at Edgewood, in the county of Allegheny and 5 State of Pennsylvania, have invented new and useful Improvements in Train-Pipe Vent-Valve Devices, of which the following is a specification.

This invention relates to fluid pressure 10 brakes and has for its principal object to provide an improved valve mechanism adapted upon a sudden reduction in train pipe pressure to effect a local venting of the train pipe.

15 In the accompanying drawing; Figure 1 is a diagrammatic view of a car brake equipment with the improved vent valve mechanism applied thereto; Fig. 2 a central sectional view of a vent valve mechanism embodying my improvement and showing the parts in normal position; Fig. 3 a fragmentary sectional view similar to Fig. 2, showing the position initially assumed by the parts upon a sudden reduction in train pipe 25 pressure; and Fig. 4 a similar view showing the position of the parts following that shown in Fig. 3.

The car brake equipment may comprise the usual train pipe 1, triple valve 2, auxiliary reservoir 3, brake cylinder 4, and branch pipe 5 leading from the triple valve to the train pipe, the improved vent valve mechanism 6 being preferably located at the juncture of said branch pipe with the train pipe 35 1, as shown in Fig. 1.

Figs. 2, 3, and 4 illustrate a preferred construction of the vent valve mechanism embodying my improvement comprising a casing 7 having an outer chamber 8 into 40 which the train pipe 1 opens, so that said chamber forms part of the train pipe volume. The casing 7 is also provided with an inner piston chamber, containing a movable abutment 9 dividing the piston 45 chamber into a chamber 10, having its capacity preferably enlarged by the addition of a small reservoir 11, and a chamber 12 adapted to communicate with the train pipe chamber 8 through a passage containing a check valve 13 adapted to prevent flow 50 of air to said chamber from the train pipe. The movable abutment 9 has a stem 14, the outer end of which is provided with a seating ring adapted to normally engage a seat

15 and thereby control communication from 55 the train pipe chamber 8 to an atmospheric exhaust port 16. Within the movable abutment 9 is provided a piston chamber for a piston 17 adapted in one position to engage a seat 18 provided at the end of the piston 60 chamber and in the opposite position to seat on a ring 19 and close communication from chamber 12 to the train pipe chamber 8. The piston stem 14 is guided somewhat loosely in a bushing 20 having openings 21 65 and 22 therein, and a small annular groove 23 is provided on the piston stem, which is adapted in the normal position of the parts to connect the opening 21 from the train pipe chamber 8 to the opening 22 which leads 70 with the triple valve branch pipe 5. The end portion of the piston 17 which engages the seat 18 is of less diameter than the piston and a differential area 24 is thus afforded which is subject to the pressure in chamber 75 10, openings 25 being provided in piston casing 26 so as to connect said area with the chamber 10. If desired, a coil spring 27 may be employed to assist in maintaining the abutment 9 in its normal position. 80

In operation, upon charging the train pipe with fluid under pressure, air flows from the train pipe chamber through the opening 21, groove 23, and opening 22 to the triple valve branch pipe 5, whence it is supplied to the triple valve to charge the automatic brake parts in the usual manner. Air also leaks around the loose stem 14 of the movable abutment 9 and charges chamber 10 and reservoir 11 to normal pressure. From 90 chamber 10 air flows through a feed groove 28 around abutment 9 to chamber 12, so that the fluid pressures on opposite sides of the abutment become equalized, and as the seated area of the stem 14 is exposed to the 95 atmospheric pressure of the vent port 16, there is a differential area of the abutment 9 subject to fluid pressure in a direction tending to seat the vent valve stem 14. A restricted passage 29 in the stem 14 connects 100 the space within the seated area of piston 17 with the vent port 16, so that said piston is subject to the unbalanced pressure of the fluid contained in the chamber 12, which tends to maintain same on the seat 18. The 105 groove 23 is of sufficient cross section to permit of such flow from the triple valve to the train pipe as required in making service ap-

lications of the brakes and also the feed groove 28 is of sufficient size to allow the pressure in chamber 10 to reduce at a rate corresponding with gradual reductions in 5 train pipe pressure, so that the opposing fluid pressures on the abutment 9 are maintained substantially equal and the same remains in its normal position. As the triple valve is thus normally connected to the train 10 pipe only through a restricted opening, undesired movement of the triple valve to emergency position under gradual reductions in train pipe pressure is prevented. Upon a sudden reduction in train pipe pressure, 15 however, fluid from chamber 12 flows past check valve 13 to the train pipe at a greater rate than the feed groove 28 can take care of, so that the abutment 9 is shifted from its normal position to an outer seat 30. The vent valve stem 14 is thus lifted from 20 its seat and fluid from the train pipe is vented to the atmosphere through port 16, to produce quick serial action throughout the train. The position of the parts is now 25 as shown in Fig. 3, from which it will be noted that although the abutment 9 is seated, the piston 17 is still away from the seat 19. Fluid therefore continues to flow from the train pipe and the pressure in chamber 12 30 correspondingly reduces, but the pressure in chamber 10 is practically bottled up, and as this higher pressure acts on the differential area 24 of the piston 17, upon a predetermined reduction in train pipe pressure, 35 dependent mainly on the extent of the differential area exposed to the pressure of chamber 10, said pressure together with the reduced train pipe pressure, which now enters through the restricted passage 29 and acts 40 on the seated area of piston 17, is sufficient to lift the piston from its seat 18. The full area of the piston 17 is then exposed to the pressure in chamber 10 and the piston is thereupon quickly shifted to its outer seat 45 19, closing communication from chamber 12 to the train pipe, as shown in Fig. 4 of the drawing. The fluid pressure in chamber 12 is now bottled up, while fluid from chamber 10 escapes through the openings 25 and 50 around the end of piston 17 to the passage 29 and the atmosphere. The pressure in chamber 12 consequently soon exceeds the pressure on the opposite side of the abutment and the same is then shifted to close 55 the train pipe vent port and shut off the further flow of air from the train pipe. Upon closing the vent port, the interior of piston 17 is connected directly to the atmosphere through the restricted passage 29 60 and consequently the reduced train pipe pressure acting on the face of the piston exposed to the pressure in chamber 8 immediately shifts the piston to its normal position.

65 In charging up the system, as the cham-

ber 10 is supplied with air only at the rate at which air can leak around the stem 14, it will be seen that danger of overcharging at the head end of the train is obviated, and this is quite important, as in such case undesired action of the vent valve mechanism might take place upon the reduction of the train pipe pressure to the normal pressure. 70

As the action of the vent valve is dependent on means adapted to operate independently of the vent valve, a much more reliable operation of the mechanism is assured. 75

Having now described my invention, what I claim as new and desire to secure by Letters Patent, is:—

80 1. In a fluid pressure brake, the combination with a train pipe, of a movable abutment subject on one side to train pipe pressure and on the opposite side to the pressure of a chamber normally charged to train pipe pressure, a valve operated by said abutment upon a sudden reduction in train pipe pressure for opening a train pipe vent port, and means for closing communication from the train pipe to said abutment upon a predetermined reduction in train pipe pressure. 85

90 2. In a fluid pressure brake, the combination with a train pipe, of a movable abutment subject on one side to train pipe pressure and on the opposite side to the pressure of a chamber normally charged to train pipe pressure, a valve operated by said abutment upon a sudden reduction in train pipe pressure for opening a train pipe vent port, and means subject to the opposing pressures of the train pipe and said chamber and operating upon a predetermined reduction in train pipe pressure by flow to the vent port for closing communication from the train pipe to said abutment. 95

100 3. In a fluid pressure brake, the combination with a train pipe, of a movable abutment subject on one side to train pipe pressure and on the opposite side to the pressure of a chamber normally charged to train pipe pressure, a valve operated by said abutment upon a sudden reduction in train pipe pressure for opening a train pipe vent port, and a piston device subject on one side to the pressure of fluid flowing from the train pipe to the vent port and to the pressure of said chamber and on the opposite side to train pipe pressure and operating upon a predetermined reduction in train pipe pressure by flow to the vent port to close communication from the train pipe to said abutment. 110

115 4. In a fluid pressure brake, the combination with a train pipe, of a movable abutment subject on one side to train pipe pressure and on the opposite side to the pressure of a chamber normally charged to train pipe pressure, a valve operated by said abutment upon a sudden reduction in train pipe pressure for opening a train pipe vent port, 120

125 130

and a piston device subject on one side on a portion of its area to the pressure of fluid flowing from the train pipe through the vent port and on another portion of its area 5 to the pressure in said chamber, and on the opposite side to train pipe pressure, for controlling communication from the train pipe to said abutment, said piston device being operated by the chamber pressure acting on 10 one side to close said communication upon a predetermined reduction in train pipe pressure by flow through the vent port.

5. In a fluid pressure brake, the combination with a train pipe, of a vent valve mechanism comprising a valve and movable abutment operating upon a sudden reduction in train pipe pressure for locally venting the train pipe and means for closing communication 15 from the train pipe to said abutment upon a predetermined reduction in train pipe pressure.

6. A train pipe vent valve device comprising a casing, a movable abutment therein subject to the opposing pressures of the train 20 pipe and a chamber, a valve operated by said abutment for controlling a vent port from the train pipe, and a piston carried by said abutment and subject to the opposing pressures 25 of the train pipe and said chamber for controlling communication from the train pipe to said abutment, said piston being adapted upon movement to close said communication and to open communication for 30 permitting the release of fluid from said chamber.

7. A train pipe vent valve device comprising a casing, a movable abutment therein subject to the opposing pressures to two chambers normally charged to train pipe pressure, a valve operated by said abutment upon a sudden reduction in pressure in one chamber 40 for opening a train pipe vent port, a piston subject to the opposing pressures of said chambers for controlling communication from one chamber to the train pipe and operating upon a predetermined reduction in train pipe pressure by venting of fluid to said vent port for closing said communication, and means controlled by said piston for opening communication to permit release 45 of fluid from the other chamber, to thereby effect the closing of the vent valve.

8. In a fluid pressure brake, the combination with a train pipe and a vent valve device operating upon a sudden reduction in train pipe pressure to vent air from the train pipe to the atmosphere, of a valve mechanism adapted, upon a predetermined reduction in train pipe pressure by the operation of the vent valve device, to effect the closure of said vent valve device and thereby 50 cut off the escape of air from the train pipe.

In testimony whereof I have hereunto set 55 my hand.

WALTER V. TURNER.
